UNITED STATES PATENT OFFICE.

WILLIAM G. DOBBS, OF AUBURN, NEW YORK.

FURNACE AND GRATE THEREFOR.

Application filed April 16, 1923. Serial No. 632,409.

To all whom it may concern:

Be it known that I, WILLIAM G. DOBBS, a citizen of the United States, residing at Auburn, in the county of Cayuga and State of New York, have invented certain new and useful Improvements in Furnaces and Grates Therefor, of which the following is a specification, reference being had to the accompanying drawings.

10. This invention relates to furnaces, and particularly to the grates thereof.

The general object of my invention is to provide a grate so constructed that it will effectively burn culm, that is very fine anthracite coal of the smallest sizes known to the trade as rice, barley, bird's-eye and screenings, these being a necessary by-product of every anthracite coal mine and being capable of being bought at from one-third 20 to one-fourth the price of the larger sizes such as egg, stove, nut and pea.

A further object is to provide a furnace having therein a grate so formed as to be capable of burning culm in combination 25 with means for forcing air into the ash pit of the furnace and up through the grate to thereby entirely consume the coal on the grate.

30. A still further object is to provide a grate of a very simple character adapted to be made in sections and thereby be disposed within an ordinary furnace in place of the ordinary grate or initially disposed in said furnace, these sections of the grate being 35 disposed in tight abutting relation to each other and each section of the grate being formed with a plurality of apertures fitted with removable perforated plugs through which the air will pass up through the grate 40 and through the coal lying thereon.

Another object is to provide a grate having air apertures so arranged as to blow the air blast from practically every angle, thus securing an even fire all over the grate, there 45 being no dead spots or zones of incomplete combustion in the coal.

Still another object is to provide a grate formed in sections and means for locking the grate sections together into such abutting relation that no air can pass upward 50 between the grate sections.

A further object is to provide a grate which may be installed without any changes or alterations in the boiler of the heater.

55. Other objects will appear in the course of the following description.

My invention is illustrated in the accompanying drawings, wherein:

Figure 1 is a front elevation of a furnace with my improved grate applied thereto; 60

Figure 2 is an enlarged section on the line 2-2 of Figure 1;

Figure 3 is a fragmentary vertical section through a portion of the furnace and my improved grate; 65

Figure 4 is a fragmentary perspective view of one of the grate bars;

Figure 5 is an enlarged vertical sectional view through one of the plugs;

Referring to the drawings, A designates 70 an ordinary boiler furnace, though it is to be understood that my invention is not limited to a boiler furnace but may be used in connection with any furnace as, for instance, a house heating furnace, whether using hot air, steam, vapor or hot water. This furnace is usually provided with a grate disposed between the fire box and the ash pit 75 B, this grate being ordinarily of such character that it may be shaken so as to discharge ashes into the ash pit, the ashes being removable through the door opening closed by the door b.

80. My invention consists in disposing within the furnace between the fire box and the ash pit a grate of the construction shown in detail in Figure 3. This grate consists of a plurality of sections 10 which in Figure 2 are shown as elongated bars. These sections may be made of any length and are 85 rectangular in cross section so as to provide lateral faces which may be abutted close against each other and in air-tight contact. These sections 10 at their opposite ends are formed with the transversely extending 90 grooves or channels 11 for the reception of a locking bar 12, this locking bar having 95 nuts 13. When this locking bar is forced down into these grooves the sections are clamped in close air-tight engagement with 100 each other and held from any movement which would tend to separate the sections and permit air leaks between the sections.

105. Each grate bar is formed in its length with a plurality of apertures 14. These apertures extend entirely through the bar and the apertures are preferably slightly tapered downward. Removably disposed in each aperture 14 is a plug 15, the exterior face of this plug being tapered to have 110 close fit in the aperture 14 and the periphery of the plug is formed with a longitudi-

nally extending series of grooves 16 opening upon the periphery of the plug, these grooves preferably being semicircular and being placed relatively close together.

5 The body of the plug is formed with a plurality of openings 17, which openings are downwardly flared. It will be noted that the grooves 16 at their lower ends approximate the outer surface of the plug, this being due to the fact that the plug tapers from its large end to its small end. When the plug is in place within the circular aperture 14, the grooves 16 form air holes and the air in the ash pit may pass upward and through the holes 16 and 17 into and through the mass of coal supported upon the grate. These apertures 16 and 17 at their upper ends are of such small size that they will prevent even the smallest 15 coal of commercial sizes from dropping downward through the grate.

Obviously the form of the grate will depend upon the form of the furnace with which the grate is intended to be used. 25 The grate made up of the sections may be round, rectangular or oval in form and the sections will, of course, conform to the shape of the grate. I may use grates of any shape and I do not wish to be limited 30 to the particular form of grate illustrated in Figure 2.

The grates are to be disposed upon a concrete or other non-heat-conducting, airtight wall 18 which extends upward from the bottom of the ash pit entirely around the furnace, as shown in Figure 2, so that the grate rests upon the concrete and the concrete seals the grate and prevents air from leaking up around the edges thereof. 35 Boiler cement may also be applied, as at 19, around the edges of the grate and above the concrete 18 so as to additionally seal the grate against leakage of air around its periphery. Preferably the grate formed of 40 the pairs of sections 10 is relatively thick, but obviously I do not wish to be limited to this, it being also advisable that the grate bars shall be of such area in cross section as to prevent the bars being warped by intense heat.

Extending into the ash pit of the furnace and sealed by the concrete 18 is an air pipe 20 which leads to a blower 21 which may be operated by any suitable motor or power 55 from any source. The blower is intended to be of a size proportionate to the capacity of the furnace and for the work designed to be done. When the door *b* is closed, it is obvious that all of the air forced into the 60 ash pit of the furnace will be forced up through the small perforation 16 and 17 and forced through the fire bed. This causes the almost complete combustion of the coal upon the grate so that actual tests 65 with this form of grate have shown that the

ash contains less than 5% unburned carbon, whereas in the normal furnace the unburned carbon will run from 18% to 60%, thus not only wasting the cost of the unburned coal but also increasing the cost of removing the ashes. In furnaces constructed in accordance with my invention all ashes removed are in the form of clinker. The high heat fuses the ash directly over the plugs and then over the whole bed of 75 the fire and thus burns practically all the carbon out of it. As a consequence, the clinker never adheres to the grate and, as a matter of fact, is easily broken with a slice bar and removed with tongs through the 80 fire door. Thus actual practice has shown that this is a very easy operation, much easier than the ordinary method of cleaning by shaking the grate and removing the dusty ashes from the pit. All dust stays in 85 the furnace and falls back into the grate to be completely burned and to form a new clinker.

It will be noticed that in my construction the holes in the plugs are extended downward so that any small particles of dust which may get into these holes will fall through freely into the ash pit. All particles lodging in them become fused with the soft clinker and are drawn out with it, but 90 some dust falls through and it is necessary to remove this dust through the ash pit. As a matter of fact, these apertures 16 and 17 do not choke up at all and this has been demonstrated by tests of this grate. 100

It will be seen that this grate eliminates the great losses in operating boilers equipped with grates as it eliminates the loss from unburned carbon in stack gases and smoke, this loss being estimated to amount to as 105 much as 35%, it eliminates the unburned combustible left in the ash, and prevents unburned coal from dropping through the grates. All these losses result from poor combustion and because the grate bars are 110 separated sufficiently to permit the dropping down of small pieces of coal into the ash pit. By my construction the air is not merely passed through the coal without becoming thoroughly mixed with it as it does where 115 ordinary grate bars are used and forced draft, but the air is thoroughly mixed with the coal in its upward passage. Thus there are no blow holes or dead spots in the fuel bed and as a matter of fact the coal gas itself is burned with the smoke and soot from the stack and these losses are thus eliminated. A furnace having my improved grate burns the lower grades of hard coal, thus reducing the initial cost of the coal and 120 as it burns the coal more completely it requires fewer tons of coal to secure the same heating result. A full-bodied flame is produced because sufficient oxygen is both supplied and mixed with the fuel and gases to 125 130

combine all the carbon while it is still in the combustion chamber. It is particularly adapted to meet the peak load as the forced draft may be applied either automatically 5 or by hand at a given time and immediately after the forced draft is applied the rate of combustion increases and this causes an immediate rise of heat. Furthermore, it will be seen that it simplifies firing, and as it 10 requires less coal requires less work by the fireman. The volume of ash is very greatly reduced and there is less necessity for cleaning out the furnace. It will be seen that the air becomes heated in the sealed ash pit 15 which has been converted into an air chamber so that this air enters the fire box at a temperature much higher than that of the boiler room. A large volume of flame is produced over the coal at all times, thus 20 burning all the gases arising from the coal. The fires, however, can be banked almost instantly, all that is required being to shut off the motor of the blower and the fire immediately dies down. On the other hand, 25 the fires after being banked for a suitable time can be started up instantly. No waiting is necessary as there is where natural draft is used.

There is one other point of particular importance in this grate, that is that it is air blast cooled. The cold air blast striking against the under face of the grate makes this grate warp-proof, thus doing away 30 with the necessity of making the grates hollow and cooling the grates by water. Furthermore, where a grate is water-cooled, it is very difficult to form air passages extending through the grate bar and where the grates 35 happen to be disposed inside the water leg of the boiler the water leg of the boiler must 40 be drilled or otherwise formed for the water connections, which is difficult and makes the use of such a grate very limited. Furthermore, there is always danger of the 45 grates leaking, letting water out, and if the water should run back any while the grates are hot they will split and crack. It is obvious that there is no danger of this character with my improved grates.

50 In actual practice the grate is made of narrow bars about $5\frac{1}{2}$ " wide and 4" thick, thus making it possible to install the grate in any type of heater or power plant, and the grate may be installed either in heaters 55 with small doors or heaters of peculiar types or shapes.

In grates constructed in accordance with this invention it has been found that the screenings or culm is so completely burned 60 that the fuel fuses together in a clinker over the whole grate, this clinker being usually about two inches thick. By inserting a slice bar underneath this clinker it may be lifted up and then will ordinarily break in 65 from two to six pieces. The side next the

grate is, of course, black and the top of this clinker usually red hot. By turning the pieces over all the good fire or live coal will drop off and by leaving the pieces of clinker near the door for two or three minutes they 70 are ready to come out. This is all that is necessary to do in order to clean out the grate and there is no necessity for the removal of ashes, as there is in an ordinary grate. As soon as the clinker is removed 75 the fire is again like new.

While I have illustrated the grates as being supported upon a concrete or cement supporting wall, I do not wish to be limited to this, as it is obvious that the grates might 80 be mounted on metallic frames to support them any desired height. The one-inch space around the grate is then sealed to make air-tight. Any cracks or openings are also sealed with cement to make the ash pit tight. 85 This eliminates the building of concrete forms and simplifies the installation of the grate.

One of the features which I desire particularly emphasized is that the fire may be 90 forced to its limits or to any desired or necessary degree and that thus I am able to increase the capacity of the plant at least one-third and in some cases twice, or in other words secure work from one boiler which 95 would formerly take two under natural draft. It may be stated that in actual practice it has been found that with grates of the character described and blowers blowing 100 the air through the fire that the temperature of the water in a hot water heating system may be raised from 80° to 205° in fifty-five minutes, whereas this usually requires from two and a half to three hours where only 105 natural draft is used.

I claim:—

1. In a furnace, a grate formed of a plurality of parallel, laterally abutted sections, each section having air apertures therethrough, all of said sections at their opposite ends having transversely extending, aligned grooves, locking bars extending transversely across all of said sections adjacent the ends thereof and disposed in said 110 grooves, the locking bars having heads wider than the grooves and engaging the outer faces of the end sections.

2. As an article of manufacture, a solid 115 grate bar, rectangular in cross section, and having flat sides and upper and lower faces, the grate bar being formed with a plurality of apertures extending entirely through the grate bar, the apertures being downwardly tapering, downwardly tapering plugs disposed in said apertures and fitting closely against the walls of the apertures, each plug having a plurality of openings extending entirely through the plug.

3. As an article of manufacture, a solid 120 grate bar, rectangular in cross section hav-

ing flat sides and flat upper and lower faces, against the walls thereof, each plug having the grate bar being formed with a plurality peripheral, longitudinally extending grooves, of apertures extending entirely through the and a plurality of openings extending en- 10 grate bar and from the upper to the lower tirely through the plug from end to end. 5 face thereof, each aperture being down- In testimony whereof I hereunto affix my wardly tapered, downwardly tapering plugs signature.

WILLIAM G. DOBBS.
